UNITED STATES PATENT OFFICE.

FERNLEY H. BANBURY, OF ANSONIA, CONNECTICUT, ASSIGNOR TO BIRMINGHAM IRON FOUNDRY, OF DERBY, CONNECTICUT, A CORPORATION OF CONNECTICUT.

SAFETY MECHANISM FOR RUBBER-MIXING MACHINES.

Application filed February 14, 1924. Serial No. 692,687.

To all whom it may concern:

Be it known that I, FERNLEY H. BANBURY, a citizen of the United States, residing at Ansonia, in the county of New Haven and State of Connecticut, have invented a new and useful Improvement in Safety Mechanism for Rubber-Mixing Machines, of which the following is a specification.

This invention relates more especially to machines for treating plastic material, such as rubber, of the type that have a casing containing a chamber in which are one or more rotors designed when rotated to break up, crush, knead and masticate the stock that is fed into the chamber, as described in Patent #1,200,070, dated October 3, 1916. In machines of this class there is a vertically movable weight located in a neck above the rotor casing which weight is lowered down upon the stock being treated and allowed to work up and down as the material is being agitated, as set forth in Patent #1,370,398, dated March 1, 1921. This weight is connected with a piston in a cylinder above the neck which piston is designed to be raised by air pressure in order that the weight may be lifted to so free the hopper door past which the weight travels, that material may be fed through the door into the mixing chamber. After the door is closed the air pressure is relieved and the weight permitted to descend and float upon the material while it is being manipulated by the rotors. It is desirable that the hopper door should be closed or nearly closed before it is possible for the weight to be lowered in order to eliminate the liability of accident to the operative of the machine, such for instance, as the failure of the air, which would allow the weight to drop suddenly while repairs were being made, or the operative is cleaning out the casing, or attempting to feed in and clear the hopper of stock by pushing it into the casing with his hands.

The object of the present invention is to provide a machine of the character described with safety means whereby the weight cannot drop or be lowered until the feed door is closed or nearly closed, and thus obviate the liability of injury to an employee.

This object is attained by arranging a safety catch in such manner that it will project into the casing in the path of the weight

and hold it up while the feed door is open, the catch being positively connected with the door by such means that closing the door withdraws the catch and opening the door forces the catch into the casing beneath the weight.

In the accompanying drawings Fig. 1 shows a section of a plastic treating machine with a safety mechanism indicated in dotted outline in the position which it takes when the hopper door is closed. Fig. 2 shows the safety mechanism with the parts in the position occupied when the door is open. Fig. 3 shows an edge view of the safety mechanism in locking position. Fig. 4 is an edge view with the safety mechanism in unlocked position.

In the machine illustrated there are two rotors 1 of well known form rotatably mounted in a chamber 2 in the casing 3. The rotors are shown as hollow in order that they may be water-cooled and the casing is also chambered for the same purpose. At the bottom of the chamber is a discharge door 4. The stock to be treated is fed into the rotor chamber through a neck 5 from the hopper 6 when the door 7 that closes the opening from the hopper to the neck, is open. The lower edge of the door is fastened to the hinge pin 8. The weight 9 is fitted to move vertically in the neck opposite the hopper door opening. A rod 10 connects the weight with a piston 11 that is movable up and down in the cylinder 12. The usual connections are made for admitting air pressure to the cylinder below the piston for lifting the weight. After the chamber has been charged the hopper door is closed and the weight allowed to descend upon the stock and float thereon while the stock is being agitated by the rotors.

Extending through the side wall into the neck below the weight when the weight is in its highest position is a pin 13. This pin is rotatable and slidable in and out in a boss 14, and it is preferred to provide the pin with a spiral slot 15 and drive a dowel pin 16 through the hub into this slot so that when the pin is rotated in one direction it will be forced inward and when it is rotated in the opposite direction it will be drawn outward. Fastened to the outer end of the pin is a rocker arm 17 and this rocker arm is connected by a link 18 with the end of a lever 19 which is fastened to

one end of the hinge pin to which the hopper door is secured.

- With this mechanism when the door is moved from its closed position, shown in Fig. 1, to open position, illustrated by dotted lines in Fig. 2, the lever through the link and rocker arm turns the lock pin and causes it to be forced inward so that its inner end will project beneath the weight. With the pin in this position the weight cannot descend even should the air pressure beneath the piston in the cylinder fail. When the door is moved from open position, illustrated in Fig. 2, to closed position, shown in Fig. 1, the lever through the link and rocker arm rotates the pin in such direction that when the door is shut or nearly shut the pin will be withdrawn from beneath the weight, leaving the weight free to be lowered. By positively connecting the locking pin with the door and causing it to move synchronously therewith the weight is prevented from dropping when the door is opened and can only drop when the door is closed, or nearly closed, thus eliminating the possibility of an operative who should be repairing, cleaning, or feeding stock into the machine, becoming injured by any accidental dropping of the weight.
- Means equivalent to those described for connecting the door with the locking pin for moving the pin in and out synchronously with the opening and closing of the door, such as will readily suggest themselves to those skilled in the art, may be employed without departing from the invention.

The invention claimed is:

1. In a machine of the character set forth for treating plastic material, a door adapted to be opened to permit the feeding of material into the machine, a weight adapted to float upon the material being treated, means for lifting the weight, means for locking the weight in its elevated position, and mechanism connecting said locking

means with the door whereby said means is caused to positively lock the weight in its raised position when the door is open and unlock the weight so that it may be lowered when the door is closed.

2. In a machine of the character set forth for treating plastic material, a door adapted to be opened to permit the feeding of material into the machine, a weight adapted to be raised and lowered past said door, means for lifting the weight, means for locking the weight in its elevated position, and mechanism connecting said locking means with the door whereby said means is caused to positively lock the weight in its raised position when the door is open and unlock the weight so that it may be lowered when the door is closed.

3. In a machine of the character set forth for treating plastic material, a door adapted to be opened to permit the feeding of material into the machine, a weight adapted to be raised and lowered past said door, means for lifting the weight, a pin adapted to engage the weight in its elevated position, and mechanism connecting said pin with the door whereby said pin is caused to be engaged with the weight in its raised position by the opening of the door and disengaged from the weight by the closing of the door.

4. In a machine of the character set forth for treating plastic material, a door adapted to be opened to permit the feeding of material into the machine, a weight adapted to be raised and lowered past said door, means for lifting the weight, a rotatable and longitudinally movable pin, and mechanism connecting said pin with the door whereby the opening movement of the door causes the rotation and projection of the pin into the path of the weight and the closing of the door causes the rotation and withdrawal of the pin from the path of the weight.

FERNLEY H. BANBURY.
